Primary Examiner — T. Chase Nelson*Assistant Examiner* — Mark Cavanna(74) *Attorney, Agent, or Firm* — Klauber & Jackson LLC(57) **CLAIM**

The ornamental design for a medical apparatus, as shown and described.

DESCRIPTION

FIG. 1 is a perspective view showing the front, top and right side of the medical apparatus of my new design;
FIG. 2 is a perspective view showing the rear, top and left side view thereof;

FIG. 3 is a top view thereof;

FIG. 4 is a bottom view thereof;

FIG. 5 is a left side view, the right side view being the mirror image thereof;

FIG. 6 is a rear view thereof; and,

FIG. 7 is a front view thereof.

The broken lines are included for the purpose of illustrating unclaimed portions of the medical apparatus and form no part of the claimed design.
